UNITED STATES PATENT OFFICE.

JOHN G. BLESSING, OF CHICAGO, ILLINOIS, ASSIGNOR TO AUTOMATIC ELECTRIC COMPANY, A CORPORATION OF ILLINOIS.

PHONOGRAPHIC TIME-ANNOUNCER.

1,343,302.

Specification of Letters Patent. Patented June 15, 1920.

Original application filed July 7, 1913, Serial No. 777,677. Divided and this application filed May 21, 1917. Serial No. 170,110.

To all whom it may concern:

Be it known that I, JOHN G. BLESSING, a citizen of the United States of America, and resident of Chicago, Cook county, Illinois, have invented certain new and useful 5 Improvements in Phonographic Time - Announcers, of which the following is a specification.

My invention relates to improvements in phonographic time announcers, and one of the features of my invention is the application of this time announcer to an automatic telephone system whereby a subscriber, by operating his calling dial, may ascertain the 10 time of day or obtain other information contained on the phonograph record. My device is arranged so as to announce the minute and the hour and to repeat this announcement every few seconds for one minute and 15 then shift to the next succeeding minute. In order to reduce the size or number of the records required to announce the time for twelve or twenty-four hours, I divide the record into two parts or two sets of grooves. 20 These grooves, instead of being spiral grooves, as in the ordinary construction, are circular. One set of grooves, of which there are sixty, corresponds to the minutes and contains impressions corresponding to the 25 numbers 1, 2, 3, etc., up to 59, the last groove containing the impression for the word "o'clock". The other set, of which there are twelve, corresponds to the hours and contains the impressions for the figures 1 to 12. 30 A separate reproducer is provided for each set of grooves and the two sets of impressions are so arranged that they do not overlap each other, so that by placing one reproducer in engagement with the proper 35 grooves of one group and the other reproducer in the proper groove of the other group, their combined announcement may be made to correspond to the hour and minute of the day. Means are provided for 40 moving the reproducer corresponding to the minute group from one groove to the next each minute and for moving the reproducer the hour group from one groove to the next each hour. When the reproducers have 45 reached the last groove, they are automatically returned to a position to engage the first groove of the corresponding group and thus seventy-two grooves, sixty in one group and twelve in the other, are sufficient to an-

ounce any time of day, and each announcement will be repeated as many times as the cylinder makes revolutions in a minute.

A further feature of my invention is the adaptation of this time announcer to an automatic telephone system, whereby any subscriber, by merely operating his calling dial to transmit the proper series of impulses, may establish connection with this time announcer and thus ascertain the time of day.

My invention will be more clearly understood by reference to the accompanying drawings, in which I have illustrated one embodiment of my invention and may be used in connection with an automatic telephone system such as that shown in application Serial No. 777,677, Patent No. 1,227,523, of which application the present application is a division.

Figure 1 is a front elevation of a phonographic time announcer embodying the 75 principles of my invention.

Fig. 2 is a section taken on line 2—2 in Fig. 1.

Fig. 3 is a section taken on line 3—3 in Fig. 1.

Fig. 4 is a section taken on line 4—4 in Fig. 1.

Fig. 5 is a section taken on line 5—5 in Fig. 1.

Fig. 6 is a fragmentary view of the cams 85 18 and 22 (Fig. 1) on an enlarged scale, so as to show more clearly the conformation of their edges.

Fig. 7 is a diagram of the phonographic record.

Before describing the telephone system shown herein, a detailed description of the construction of the time announcer will be given. Referring to Fig. 1, there is mounted on the top of a suitable plate 13 a modified phonograph machine consisting of a frame 14 and cylinder 3, on which cylinder is a record with two sets of impressions, one set comprising a separate impression for each of the sixty minutes in an hour and the other set comprising a separate impression for each of the hours in a day. These impressions form complete rings around the record, unlike the usual impressions, which are helical. The cylinder 3 is fastened to a shaft 7 which is in turn secured to the pulley 6. For the purpose of revolving the cylinder 3, there is mounted on the under-

side of the plate 13 a small motor 2 connected by means of a belt 5. The speed of the motor is governed by a suitable governor 8. Upon a shaft 15 there are mounted two carriages 9 and 9^a for the purpose of carrying two microphone reproducers 11 and 11^a back and forth, there being one set of reproducers for each set of impressions on the record, namely, the hour impressions and the minute impressions. The reproducers are pivotally mounted on carriages by means of the screws 10 and 10^a (Figs. 4 and 5) in such a manner as to allow the reproducers to rest lightly on the record. These reproducers are provided with lugs 11^b and 11^c which extend over a portion of the edge of the carriages 9 and 9^a so that they may be lifted from the record by tipping the carriages backward. The carriages 9 and 9^a are arranged to slide back and forth independently of each other on the shaft 15, which is preferably hollow, and located inside of same are two helical springs 16 and 17. The purpose of these springs is to return the reproducers to their normal positions. For instance, the hour reproducer 11 is returned at the end of twenty-four hours and the minute reproducer is returned at the end of sixty minutes. The reproducer 11 is moved along the shaft 15 by means of the helical cam 18 against the compression of the spring 16, while the reproducer 11^b is moved along against the pulling tension of the spring 17 by means of the helical cam 22, as will hereinafter be more fully described. On the shaft 21 there is mounted a ratchet wheel 20 (Fig. 2) and adjacent thereto is an arm 23 which swings loosely on the shaft 21 and carries near its lower end a driving pawl 26 which engages with the teeth of the ratchet wheel 20. The lower end of the arm 23 is connected with the plunger 24 of a solenoid 25. Secured to the plunger 24 is a helical spring 38, so that when said plunger is drawn into the solenoid the spring 38 is compressed. Upon the deenergization of said solenoid, the power stored up in the spring 38 returns the plunger 24 to its normal position. In this way the arm 23 may be moved back and forth to rotate the ratchet wheel 20 and shaft 21 with a step-by-step movement. A holding pawl 27 is provided for the purpose of preventing all backward movement of the wheel 20 when the pawl is being moved back by the plunger 24 to engage with a new tooth. The plunger is regulated and allowed to be drawn back just so far by means of a metal disk 29 on the inside of the solenoid and a thumb screw 28, thus allowing the desired amount of clearance at the pawl 26. The helical cam 22 is mounted on and firmly secured to the shaft 21. This cam increases in height or width around its circumference by regular series of rather

abrupt steps, as indicated more clearly in Fig. 6. On the right-hand end of the carriage 9^a is a projection 30^a which is, at the beginning of an hour, at the extreme right of the shaft 15 and in contact with the narrow portion of the cam 22. Upon the ratchet wheel 20 being rotated step by step in a manner already described, the cam 22 is also turned a corresponding distance, and as each of the steps in the cam passes the projection 30^a of the carriage 9^a, said carriage is moved a slight distance to the right, sufficient to move the reproducer 11^a to the next impression on the record. During the beginning of each advancement of the cam 22, the projection 30^a of the cam 9^a moves forward a short distance with the step in the face of the cam, before riding up over it. This forward movement of the projection 30^a rocks the carriage 30^a slightly on the shaft 15, whereby the reproducer is lifted off the record before it is moved laterally. Before the cam completes its movement, it passes the projection 30^a, so that when the cam comes to rest, the reproducer drops back onto the record. This lifting of the reproducer while it is being moved laterally is to prevent the scratching of the record. The cam 22 is provided with fifty-nine steps on its surface, so that during one complete revolution of the cam, the reproducer is moved fifty-nine spaces to the left. On the sixtieth advancement the projection 30^a slips off the high part of the cam and the spring 17 returns the carriage and reproducer to their normal positions. During this return of the carriage, the projection 30^a bears on the guide 31^a which is secured to and revolves with the cam 22 and serves to hold the reproducer off the record until it gets back to its normal position.

The reproducer 11 is moved along the record by the cam 18 in substantially the same manner in which the reproducer 11^a is moved by the cam 22, as hereinabove explained. The cam 18, however, has only twenty-three steps on its surface and is adapted to make a complete revolution in twenty-four steps. The cam 18 is advanced one step on each complete revolution of the shaft 21 in the following manner: At 32 (Figs. 1 and 4) there is seen an arm loosely mounted on the shaft 15 and attached to the bottom of said arm is a pawl 33, together with the spring 34^a, for the purpose of holding said pawl 33 constantly in contact with the ratchet wheel 35. The center of the arm 32 is arranged to fit around the shaft 21, as clearly shown in Fig. 4. The cam 18 is securely attached to the ratchet wheel 35 and both are mounted loosely on the shaft 21 and therefore do not revolve with the ratchet wheel 20 and the minute cam 22, which are both secured to the shaft 21. There is fastened to the frame 14 a flat 130

spring 35^a that bears on the arm 32, holding it normally against the shaft 21 and at the same time holding the pawl 33 rigidly against the ratchet wheel 35. A spiral cam 5 is shown at 36 which is securely fastened to the shaft 21 and consequently turns with each step-by-step movement of the ratchet wheel 20, which latter, it will be remembered, is operated by means of the energization 10 and deenergization of the solenoid 25. As the cam 36 turns it pushes against a projection 39 on the movable arm 32, which arm is thereby pressed back against the tension of the spring 35^a and draws the pawl 15 33 back a proportionate distance toward the next tooth on the ratchet wheel 35. When the highest part of the cam 36 reaches the projection 39, the cam 34 is forced back far enough to engage a new tooth of the 20 wheel 35, and when the cam completes its revolution and the projection 39 slips off the high part of the cam, the arm 32 is returned to its original position by the spring 35^a, and the wheel 35 is thereby advanced one 25 step. Both reproducers are normally held off the record by the engagement of the tail pieces 47 and 48 of the carriages 9^a and 9 with the bars 45 and 46, as indicated more clearly in Fig. 5. These bars are carried on 30 the end of the arms 43 and 44 which are secured to a shaft 42, to which latter is also secured the armature 41 of an electromagnet 40 (Fig. 3). By the energization of the magnet 40, the shaft 42 is turned slightly 35 to tip the bars 45 and 46 back far enough to permit the reproducers to drop down onto the record.

In Fig. 7 there is represented in a more or less diagrammatic form a cylindrical record for the time announcer described herein, said record being developed into a plain surface. At X is shown the record grooved corresponding to the hours. These grooves are twelve or twenty-four in number, each one comprising the proper impressions for reproducing some one of the words "one," "two," "three," etc., up to "twelve." If these grooves are twenty-four in number, the record impressions run from 45 "one" to "twelve" and then repeat. This enables each groove to be used only during one hour of the twenty-four, while if only twelve grooves are used, each one would have to be used twice during the twenty-four hours, thereby decreasing the life of the record. The hour impressions on the record all begin approximately on a straight line $x-x$ across the record and extend only about one-third or less of the distance 50 around the cylinder. The minute impressions W are sixty in number, running from "one" to "fifty-nine," the sixtieth being for the word "o'clock." The minute impressions all begin approximately on the 55 line $w-w$, which is beyond the end of the

longest impression of the hour group. The record is placed on the constantly rotating cylinder 3 (Fig. 1), with the reproducer 11 in position to engage the hour group of impressions X and the reproducer 11^a in position to engage the minute group of impressions W. The reproducer 11 is set to engage the particular impression in the group X corresponding to the hour of the day and the reproducer 11^a is set to engage the impression of the group W corresponding to the minute of the hour. It is thus seen that when the reproducers are in contact with the record, the time will be announced once during each revolution of the record, the 70 reproducer 11 first announcing the hour and the reproducer 11^a announcing the minute immediately thereafter. The cylinder is preferably revolved at the rate of fifteen or twenty revolutions per minute, so as to give 75 an announcement every three or four seconds. The magnet 25 (Fig. 2) is connected with a suitable clock mechanism, which closes the circuit of the magnet once each minute to move the reproducer 11 to 80 the next impression. At the beginning of each hour the reproducer 11^a is moved from the "fifty-nine" impression to the "o'clock" impression and the reproducer 11 is moved over one step to the impression corresponding to the new hour. Although the reproducers are constantly in position to give the correct announcement, they are not always in actual engagement with the record, for, 85 as has been explained, means have been provided for holding the reproducers off the record at all times except when an announcement is desired.

It will thus be seen that I have devised a very efficient phonographic announcer, 105 and while I have illustrated one specific embodiment of my invention and have shown this in connection with an automatic telephone system of a particular type, it will, of course, be understood, that my invention 110 is capable of many modifications and changes. Thus, while I have shown the cylinder provided with two groups of impressions and two reproducers in order to record the time of day, it is obvious that the record 115 might be provided with a separate impression for each minute of the twelve hours and only one reproducer employed, which reproducer would be stepped along one step each minute and returned to its starting 120 point once in twelve hours. Likewise, while I have referred to my announcer as a time announcer, it is, of course, understood that this device can be used for imparting any other information, or for advertising purposes, or, if desired, these features can be combined, as, for example, each groove could contain a time announcement together with some advertisement, or items of news could be interpolated when desired. Likewise, I 125 130

do not wish to be limited to the form of telephone system with which I have chosen to illustrate my invention, as it is obvious that my invention is adapted for use in connection with other forms of automatic or semi-automatic systems.

What I claim as my invention is:

1. In a phonographic announcer, a continuously moving record having a plurality of circular grooves, a stylus adapted to engage said grooves, and automatic means for disengaging said stylus from one groove and then shifting the same to the next succeeding groove at predetermined time intervals.
2. In a phonographic announcer, a continuously moving record having a plurality of circular grooves, a stylus adapted to engage said grooves, automatic means for shifting said stylus from one groove to another at predetermined time intervals, and means for automatically returning said stylus to normal position after it has been moved a predetermined number of steps.
3. In a phonographic announcer, a continuously moving record having a plurality of circular grooves, a stylus adapted to engage said grooves, automatic means for shifting said stylus from one groove to another at predetermined time intervals, means for automatically returning said stylus to normal position after it has been moved a predetermined number of steps, and means for holding said stylus out of engagement with said grooves during said return movement.
4. In a phonographic announcer, a record having two sets of circular grooves, a stylus adapted to engage each of said sets of grooves, means for automatically raising one stylus from one of said grooves and shifting the same laterally to a second groove at predetermined time intervals, and means for automatically raising and shifting the second stylus after a predetermined movement of said first stylus.
5. In a phonographic announcer, a record having two sets of circular grooves, a stylus adapted to engage each of said sets of grooves, means for automatically raising one stylus from one of said grooves and shifting the same laterally to a second groove at predetermined time intervals, and means for returning said stylus to normal position after it has been moved a predetermined number of steps, and means for automatically raising and then shifting said second stylus one step for each predetermined series of steps of said first stylus.
6. In a phonographic announcer, a record having a series of circular grooves, a stylus adapted to engage said grooves, a cam, step-by-step means for operating said cam, and means controlled by said cam for first disengaging said stylus from said record and then shifting same to the next succeeding groove at predetermined time intervals.
7. In a phonographic announcer, a record having two sets of circular grooves, a stylus adapted to engage with the grooves of each set, a rotary cam, step-by-step means for operating said cam, means controlled by said cam for first disengaging said stylus from the record and then shifting the same to another groove at predetermined time intervals, a second rotary cam adapted to be rotated one step for each complete rotation of the first cam, and means controlled by the second cam for first disengaging said second stylus from the record and then shifting the same to another groove.
8. In a phonographic announcer, a record having a series of circular grooves, a stylus adapted to engage said grooves, a carriage upon which said stylus is mounted, a circular cam, and means for rotating said cam in a step by step manner, said cam having means for engaging said carriage so as to rock the same to disengage said stylus from the record and to then shift the stylus from one groove to the next, at predetermined time intervals.

Signed at Chicago, Cook county, Illinois,
this 15th day of May, 1917.

JOHN G. BLESSING.
